COMBINED BIBLE RACK AND CROSS

Harley Ammermann, Box 526,
Clara City, Minn. 56222

Filed Apr. 12, 1973, Ser. No. 350,385

Term of patent 14 years

Int. Cl. D6—04

U.S. Cl. D6—184

Fig. 1

Fig. 5

Fig. 2

Fig. 6

Fig. 3

Fig. 4

FIG. 1 is a perspective view of a combined bible rack and cross showing my new design;

FIG. 2 is a front elevational view thereof;

FIG. 3 is a right side elevational view;

FIG. 4 is a rear elevational view;

FIG. 5 is a top plan view, and

FIG. 6 is a bottom plan view.

I claim:

The ornamental design for a combined bible rack and cross, substantially as shown.
